UNITED STATES PATENT OFFICE.

CHARLES E. LUCKE, OF NEW YORK, N. Y., ASSIGNOR TO WORTHINGTON PUMP AND MACHINERY CORPORATION, OF NEW YORK, N. Y., A CORPORATION OF VIRGINIA.

INTERNAL-COMBUSTION ENGINE.

Application filed July 25, 1921. Serial No. 487,259.

This invention relates to improvements in piston and cylinder heads for internal combustion engines.

Internal combustion engines of large size, 5 and especially Diesel oil engines, require piston and cylinder heads strong enough to resist high internal pressures, and of such construction as not to be injured by a high rate of heating even after long service. The 10 pressures in the combustion chamber to which such piston and cylinder heads may be subjected may rise as high as 1000 lbs. per square inch and the rate of heat transmission which they may be expected to endure will often be much in excess of the 15 practice in the most severely heated sections of steam boilers.

In my invention the metal wall of the piston or cylinder head which is directly 20 subjected to the high heat and pressure of the combustion chamber is made as thin as possible in order to transmit the heat at the required rate without rising to a temperature which would injure such wall, and, 25 in order to provide sufficient strength to resist the high pressures to which it is subjected, the thin wall is made of wrought metal, while the structure of the piston or cylinder head is such as to support the thin 30 pressure-receiving wall so as to prevent distortion thereof, and at the same time provide a space for cooling water. By such a construction I provide a body of cooling water in the piston or cylinder head separated 35 from the combustion space by a very thin metal wall, whereby the temperature of the wall is maintained low enough to prevent injury to the metal, and I provide the necessary strength of wall to prevent 40 distortion by using wrought metal for the thin wall and suitably supporting or bracing it. The ductility of the wrought metal, that is to say, forged or rolled metal, is such that it will stand elongation within 45 its elastic limits without injury, and in my invention I utilize this property.

By providing a piston head and a cylinder head which will successfully withstand high temperatures it becomes possible to raise 50 the temperature limit now fixed in practice for internal combustion engines and thereby to obtain an increased rating or horse power per cylinder for the sizes of engines now constructed, so that there results not only a lower cost but a less weight per

horse power. Furthermore, the range of utility of the internal combustion engine is materially extended by a piston head and cylinder head embodying this invention, for the reason that it becomes possible to construct such engines having cylinders larger than heretofore possible. Up to this time Diesel engines having cylinders larger than 36 inches in diameter have not been successful, principally because of the failures of 60 the heads. This difficulty is overcome by the present invention, so that internal combustion engines particularly of the Diesel type and with cylinders larger than 36 inches diameter become practical for ship work 65 thereby materially enlarging the field in which said engines may be employed in marine navigation.

Cylinder heads embodying the invention 70 are particularly applicable for aerial engines as it is possible to employ a light metal such as aluminum or light alloys for the cast members of the head and provide a very thin rolled steel wall for contact with the hot gases, the thin steel wall being united 75 with the aluminum casting so as to form one unitary structure as, for example, by welding or soldering the steel to the aluminum. In this way there is obtained a strong, removable cylinder head of relative light 80 weight and capable of successfully withstanding temperatures higher than those now encountered in aerial engine work.

The invention will be more particularly 85 described in connection with the accompanying drawings, and then pointed out hereinafter.

In the drawings:

Fig. 1 is a section on the line 1—1, Fig. 2, through a cylinder head embodying my 90 invention, the valves and their cages being omitted;

Fig. 2, a section on the line 2—2, Fig. 1;
Fig. 3, a section on the line 3—3, Fig. 1;

Fig. 4, a section on the line 4—4, Fig. 2;
Fig. 5, a section of a piston head embodying 95 my invention;

Fig. 6, a section on the line 6—6 of Fig. 5.
Fig. 7 is a section of another form of 100 cylinder head embodying my invention; and

Fig. 8 is a section of the same on the line 8—8, Fig. 7.

Referring to the drawings, and particularly Figs. 1 to 4 inclusive, A indicates a cylinder wall and B the cylinder water jack- 110

et of an internal combustion engine. The cylinder head is held to the cylinder in any suitable way. In the example illustrated, long bolts C are provided, which extend through suitable openings in the cylinder down to any suitable part of the engine, not shown, nuts c being provided in contact with the outer face of the head.

The cylinder head comprises a thin wrought metal wall member D arranged to form one wall of the combustion chamber. The wall member shown is circular and has a diameter somewhat greater than the interior diameter of the cylinder. It has its periphery set into a recess or rabbet in the edge of a wrought metal hemisphere or dome E. The wall member D is braced by a series of circular and radial bracing members. In the present example the circular members are arranged concentrically with each other, with their axis passing through the center of the hemisphere. The inner circular member is indicated at F₁ and the outer one at F₂. The radial members, in the example illustrated, comprise diametrically arranged members F₃ and a series of outer members F₄ located between the outer circular member F₂ and the dome E.

At the junction of inner circular member F₁ with a radial member F₃, there is a tube G₁ for the reception of a fuel spraying device, not shown. A similar tube G₂ is located at the junction of one of the diametrical members F₃ and the outer circular member F₂. This tube may be used for connection of an air-starting valve or of an indicator of the type of the steam-engine indicator for giving diagrams of operation.

To the outside of the dome E are secured a plurality of stirrups or hollow ribs H, Figs. 3 and 4, through which pass the tie bolts C. The dome E and the other parts hereinbefore described are enclosed in a casing comprising side walls I flanged inward at the part next the cylinder, as indicated at i, Fig. 4, and a cap or lid I'.

The head is provided with what may be designated as T-connections arranged to receive valve cages for the air-inlet and the exhaust valves, respectively. In the particular example illustrated the T-connection for the exhaust valve is shown as somewhat larger than that for the air-inlet valve and comprises a tubular part K having a reduced diameter at its end next the cylinder, thus providing a shoulder indicated at k which serves as a seat for the valve cage. The tubular part K has its axis parallel to the axis of the cylinder and may be designated as the axial portion of the T-connection. To this portion K is connected a lateral tubular portion K₁ which is the outlet for the exhaust gases.

The T-connection for the inlet valve has its axial portion indicated at K₂ and its lat-

eral portion at K₃. The two outer ends of the lateral portions K₁ and K₃ are inserted through holes in a flange plate L whereby they are retained at the proper distance apart and whereby they may be readily connected to suitable piping, not shown, for the air-supply and exhaust discharge.

In making the cylinder head hereinbefore described, two separate T-connections are first inserted in place in the dome E and 75 welded to the dome both at its top and at its side by electric arc welding or oxy-acetylene welding. The brace members F₁ to F₄ inclusive, as well as the tubes G₁ and G₂ are built as a separate unit or spider, the parts 80 being welded together by the same type of welding as mentioned above. With the dome E upside down, the said separate unit or spider is slid into place around the axial portions K, K₂, and is welded to the dome and to said axial portion at such places as 85 can be reached conveniently by the arc or oxy-acetylene process.

The hollow ribs H are then welded to the outside of the dome E. The casing I is then 90 put in place and welded to the dome along the line of junction the flange i with the outside edge of the dome E. Then the wall member D is put in place and welded to the inner rabbeted edge of the dome E and to the inner ends of the axial portions K, K₂ of the T-connections. The cap or cover plate I' may then be put in place and welded to the casing I. The flange plate L is then placed on the ends of the lateral extensions 95 K₁, K₃ and welded to them. This gives a 100 strong water-jacketed cylinder head which may be held to the cylinder by suitable bolts and nuts such as C, c.

In the particular construction shown in 105 the drawings, the flange i of the casing I is provided with suitable water passages or holes as indicated in Fig. 4, whereby the water space around the cylinder is put in 110 communication with the water space in the cylinder head. Also the dome E and the various bracing members F₁ to F₄ may be provided with suitable openings or perforations to allow the water to circulate freely 115 through the head.

In Figs. 5 and 6 I have illustrated one 120 form of piston head construction for gas-engines embodying my invention. In this construction the wall member which separates the combustion chamber of the engine from a water jacket is the thin wall indicated at D'. This is made of thin wrought metal and is flanged as shown at d'. It rests upon and is welded to a cylindrical body of suitable metal, most advantageously 125 cast iron, as indicated at M, Fig. 5. The piston body M is formed of sufficient thickness to sustain the compressive strains to 130 which it may be submitted and to carry the packing rings M'.

The piston rod N is shown as hollow and preferably has two ducts, as indicated at n, n₁, for the circulation of cooling water to the interior of the piston. The cooling water is supplied to the piston rod in any of the well-known ways (not shown). The end of the piston rod to which the piston head is connected is flanged as indicated at N' and this flange fits within the piston body M, to which it is fixed by welding.

Between the wall D' of the piston and the flange M, is arranged the means for bracing the wall D'. In the present example this means comprises a plurality of concentric members P₁, P₂, P₃, which are braced laterally by web members Q, Q₁, suitably welded in place.

The members P₁ to P₃, inclusive, and the web-members Q and Q₁, inclusive, are provided with openings for the passage of the circulating water.

In Figs. 7 and 8 I have shown another embodiment of the invention, wherein the dome E is omitted and the cover plate or lid so dimensioned and braced that it may itself carry the thrust of the gas pressure on the wrought metal wall. In the best embodiment of this form of the invention the cover plate I₂, the wall I₃ and its flange i₃ may be of cast metal, the wall plate D₂ of thin rolled sheet steel being welded to the flange i₂. Furthermore, in carrying out this modification in its simplest form, the bracing members for bracing the wall-plate D₂ may be ribs cast integral with the cover plate I₂, as indicated at F₄, Figs. 7 and 8. Finally, if desired, the cover plate I₂ with its bracing ribs F₄ and the wall I₃ with its flange i₃ may all be cast in one piece, the thin wrought metal wall plate D₂ then being secured to the flange i₃ by welding.

From the above description it will be clear that in my invention there is provided a head in which only thin wrought metal comes in contact with the hot gases.

What I claim is:

1. A head to receive the axial thrust of the pressure in the combustion space of an internal combustion engine, said head having a water-tight water-space and a relative-

ly thin wrought-metal wall arranged to contact on one side with the water in the water-space and to contact on the other side with hot gases in the combustion space, said head also having means for bracing said wall 55 against pressure due to said gases, said bracing means comprising a plurality of concentric cylindrical members of thin wrought metal arranged in the water-space, and a rigid abutment member against which 60 said thin members react.

2. A piston head having a water-tight water-space and a relatively thin wrought metal wall arranged to contact on one side with the water in the water space and to 65 contact on the other side with hot gases in the combustion space, said head having a body of cast metal comprising an end and a cylindrical portion to which the thin metal wall is welded, said cast metal body being 70 arranged to carry the packing rings, said head also having means for bracing said thin wrought metal wall against pressure due to said gases, said bracing means comprising a plurality of members of perforated 75 thin wrought metal located in the water-space and arranged to transmit the pressure on the said thin wall to the end of the cast body.

3. A piston-head having a water-tight 80 water space and a relatively thin wrought-metal wall arranged to contact on one side with the water in the water-space and to contact on the other side with hot gases in the combustion space, said head having a 85 body of cast metal comprising an end and a cylindrical portion to which the thin metal wall is welded, said cast metal body being arranged to carry the packing rings, said head also having means for bracing said 90 thin wrought-metal wall against pressure due to said gases, said bracing means comprising a plurality of concentric cylindrical members of perforated thin wrought-metal located in the water-space and arranged to 95 transmit the pressure on the said thin wall to the end of the cast body.

In testimony whereof, I have hereunto set my hand.

CHARLES E. LUCKE.
